UNITED STATES PATENT OFFICE.

FRANK H. MEINERS, OF CINCINNATI, OHIO.

FLUSHING-VALVE.

1,218,793.

Specification of Letters Patent. Patented Mar. 13, 1917.

Application filed March 27, 1916. Serial No. 86,990.

To all whom it may concern:

Be it known that I, FRANK H. MEINERS, a citizen of the United States, residing at Cincinnati, in the county of Hamilton and State of Ohio, have invented certain new and useful Improvements in Flushing-Valves, of which the following is a specification.

My invention relates to flushing valves, especially for water-closet tanks. Its object 10 is to simplify devices of this character, and to render them more reliable and less liable to derangement and leakage.

My invention consists in the combination of parts and in the details of construction 15 and arrangement of parts, as will herein be more fully described and claimed.

In the drawing:

Figure 1 is a vertical sectional view through one end part of a tank and a device 20 embodying my invention, mounted therein, parts being shown in flushing position by dotted lines;

Fig. 2 is a sectional plan view, the section being on a plane corresponding to the 25 line 2—2 of Fig. 1;

Fig. 3 is an inverted sectional plan view, the section being on a plane corresponding to the line 3—3 of Fig. 1;

Fig. 4 is an enlarged vertical section of 30 the valve-seat ring.

Where used in a tank, as indoors, and as shown in Figs. 1, 2 and 3, there is a valve-body 1 with a side chamber 2 into which runs an overflow pipe 3, the height of which 35 pipe 3 determines the maximum height A of water in the tank 4. This body 1 has a neck 5 extending through the bottom 6 of the tank 4, with a flange 7 having a gasket 8 between it and the bottom 6; and there is a 40 nut 9 screwed on the neck with a gasket 10 between it and said bottom. The usual flushing pipe 11 connects with the lower end of the neck 5, to lead to the closet bowl, not shown.

The top of the body 1, above the side 45 chamber 2, has its interior diameter less than that of the neck 5; and comprises a lower continuous interiorly threaded part 12 and an upper part with lateral openings 13. Into the threaded part 12 is screwed an 50 exteriorly threaded ring 14 with its upper interior increasing in diameter upwardly with a straight taper, as best seen in Fig. 4. Its lower edge has notches 15, in which a 55 spanner may be engaged to screw the ring into the threaded part 12 of the body 1.

The upper part of the ring forms the annular seat for the valve member, which is in the form of a downwardly tapered valve-plug 16; the taper of the plug being 60 such the plug wedges securely in its seat. This plug is screwed onto the lower end of a stem 17, and the top of the body 1 has a tubular continuation with interior diameter uniform with that of the upper interior of 65 the body; this continuation being preferably in the form of a thin tube 18 screwed into the valve-body top, as shown. Onto the top of the continuation or tube 18 is screwed a cap 19, with a central hub 20 70 having a central opening through which extends the stem 17 to be guided thereby. The upper perimeter of the plug is only very slightly less in diameter than is the interior of the body 1 and tube 18. Thus, the valve-plug and stem may slide up and down in the body 1 and tube 18, and the plug will be accurately guided into its seat.

The upper end of the stem 17 has an eye 21, and a lever 22 has a fork 23 receiving the eye 21, between its members, with a pin 24 through its members and the eye. The lever 22 has a fulcrum 25 on the upper edge of the tank 4; and its other end, outside the tank, has, as here shown, a chain 26 connected to it, with a handle 27 on the lower end of the chain. The parts are so proportioned that the valve-plug 16 against the resistance of the water below it in the hollow upward extension only slightly overbalances 90 the handle 27. It will be understood that the chain 26 and handle 27 may have substituted for them any other well known devices. For instance, with a "low-down" tank, any of the various kinds of handles or 95 levers used on "low-down" tanks, may be used depending upon circumstances. But in any instance, the valve-plug and attached parts must slightly overcome the opposition 100 of these other parts.

Thus constructed, when the chain 26 or its equivalent is pulled down, the valve-plug 16 is raised through the tubular guideway to a position about as indicated by the dotted lines in Fig. 1. This allows the water 105 to rush out through the openings 13, past the valve-seat, and down through the flushing pipe 11 to the bowl. Owing to the nearly balanced condition of the valve-plug 16, it does not descend quickly when the 110 chain 26 is released; but slow enough to allow an ample flushing period before the

plug wedges in its seat, thus cutting off the flow until it is raised again.

It will be seen that the parts are few, and have a very simple relation to each other, and all but the gaskets 8 and 10 may be of metal, eliminating the use of rubber or other soft material in the valve itself. As the valve-seat wears, the plug 16 sinks lower into the ring 14; and when this ring 10 is worn through enough to impair the efficiency of the seat, a new ring 14 may be substituted for it. This is done by disconnecting the flushing pipe 11, reaching the ring 14 from the bottom exterior of the tank, 15 without the necessity of disturbing the parts inside the tank.

I claim:

In combination, a hollow body with an interior valve aperture and an upwardly facing annular valve-seat around said aperture and with upper and lower openings respectively entirely above and entirely below said valve-seat, a hollow extension on said body extending upward from above said upper opening, an inclosure outside

said body and extension, communicating with and adapted to confine water in communication with said upper opening, a downwardly tapered valve-plug, sliding down in said extension past said upper opening and wedging down in said valve-seat entirely below said upper opening, or sliding up in said extension far enough past said upper opening to have its fall retarded by water below it in said extension, and withdrawn entirely from said valve aperture, and means connected to said valve-plug to oppose the downward sliding of said valve-plug, in such degree that it is only slightly overcome by said valve-plug falling against the resistance of the water in said extension when said valve-plug is raised past said upper opening as aforesaid and there is a continuous body of water communicating through both of said openings and the valve aperture.
